UNITED STATES PATENT OFFICE.

SERGEY DARK SMOLIANINOFF, OF WASHINGTON, DISTRICT OF COLUMBIA.

EXPLOSIVE.

SPECIFICATION forming part of Letters Patent No. 672,991, dated April 30, 1901.

Application filed December 30, 1899. Renewed September 15, 1900. Serial No. 30,186. (No specimens.)

To all whom it may concern:

Be it known that I, SERGEY DARK SMOLIANINOFF, a citizen of the United States, residing at Washington, in the District of Columbia, have invented new and useful Improvements in New High Explosives, of which the following is a specification.

I have discovered a new chemical compound for an explosive that is absolutely safe to handle, whether in a liquid or solid or powdered or gelatinous form, under all conditions of transportation, storage, or use, and which will remain stable and entirely unaffected by heat and cold, moisture, climate, and atmospheric changes. This explosive compound is composed of nitroglycerin, empyreumatic oil, (principally obtained from the distillation of wood-tar,) and oil of mirbane in varying proportions, according to the strength of explosive required. The empyreumatic oil which I prefer to use is a light oil of wood-tar, sometimes known as "spirit of tar," (*Oleum picis liquidae*.)

The explosive may be ordinarily prepared in about the proportions of the constituents named, as follows: nitroglycerin, seventy per cent., by weight; empyreumatic oil, (oil of wood-tar,) fifteen per cent., by weight; oil of mirbane, fifteen per cent., by weight. These proportions may, however, be varied as desired without affecting the compound except as to degree of explosive force. It is preferable to first mix together the empyreumatic oil and the oil of mirbane in desired quantities or proportions and then add this first mixture to a suitable proportion of nitroglycerin, all the ingredients to be then thoroughly mixed together.

In order to obtain a granulated explosive or to permit molding or shaping of the compound into desired forms, I may add to the above-named mixture of nitroglycerin, em-

pyreumatic oil, and oil of mirbane a suitable proportion of magnesia or granulated charcoal or wood-pulp or any appropriate substance or substances to give bulk and body to the compound and vary its consistence. This compound may be readily molded in various forms, if desired, or it may be formed into a sheet to be cut into strips or blocks. A small quantity of any suitable resin or gum substance may be added if a gelatinized explosive is desired.

This compound of nitroglycerin, empyreumatic oil, and oil of mirbane can be prepared in such proportions as to give a very great explosive force and yet be handled with the most perfect safety under all circumstances attending its transportation, storage, and use, whether as a liquid or in the form of powder, granules, gelatin, or in a more or less solid state.

This explosive compound will not decompose but will remain absolutely stable until used. It is not exploded by friction, compression, or concussion; it is not affected by air, heat, or water; it will stand exposure to high temperatures without explosion or decomposition, and it will not freeze.

In using this compound it is to be exploded by any fulminate, chlorate, or detonating explosive.

What I claim as my invention is—

A new explosive compound composed of nitroglycerin, empyreumatic oil and oil of mirbane, substantially as described.

In testimony whereof I have hereunto set my hand in presence of two subscribing witnesses.

SERGEY DARK SMOLIANINOFF.

Witnesses:

GEO. W. REA,
GEO. E. SULLIVAN.
